UNITED STATES PATENT OFFICE

JACK KUGELMAN, OF PHILADELPHIA, PENNSYLVANIA

STOCKING

Application filed June 11, 1931. Serial No. 543,600.

This invention relates to a stocking construction and has for its primary object the designing of the hem portion of the stocking to facilitate the folding of portions thereof to regulate the length of the stocking when in use.

An object of the invention resides in providing the hem with a plurality of foldable sections each of which being of a particular width to accurately determine the length of the stocking when in use.

Another object of the invention resides in the difference in width of the foldable sections of the hem to compensate for the thickness of the folds as they are formed.

A feature of the invention resides in the utilization of duplex sets of openings defining a foldable band which facilitates the folding of the sections of the hem along definite lines.

Besides the above my invention is distinguished in the use of a plurality of spaced reinforced portions performing the triple function of forming a plurality of foldable sections, of reinforcing the stocking against runs at a plurality of points and of facilitating the folding of the hem of the stocking along predetermined lines.

With these and other objects in view the invention will be better understood from the following detailed description taken in conjunction with the drawings wherein:

Figure 1 is a side elevation of a stocking constructed according to my invention.

Figure 2 is the upper portion of the stocking with one of the sections in folded position.

Figure 3 is an enlarged fragmentary view.

Figure 4 is an enlarged fragmentary view of a portion of the upper edge of the stocking when one of the sections has been folded, thereby producing a picot effect.

Again referring to the drawings illustrating one of the many constructions of my invention the numeral 1 designates the hem portion of the stocking 2. This hem portion 1 is structurally changed at predetermined spaced points to define a plurality of foldable sections 3. One manner of folding the foldable sections 3, as shown in the drawings is to

provide a plurality of openings 4, preferably arranged in spaced duplex sets hereinafter known as an upper set 5 and a lower set 6. These sets are spaced predetermined distances apart to form foldable bands 7 that facilitate the folding of the sections 3. Due to the formation and arrangement of the openings 4 and the defining of the bands 7 the hem will be reinforced at the various bands 7 in manners well known in the art such as by lock stitching. The duplex sets of openings are spaced unequal distances apart as clearly indicated in Figures 1 and 2, so as to compensate for bulging of the hem as folded and thereby accurately determining the length of the hosiery and producing a much neater effect.

I am aware of the fact that a stocking has been heretofore manufactured including in its construction a reinforcement at the junction of the hem and leg portion of the stocking, the reinforcement being of a nature to define a plurality of openings, but I am of the opinion that I am the first to provide a plurality of openings, a plurality of reinforcements and defining a plurality of foldable bands for facilitating folding operations and preventing "runs."

I am of the opinion that I am the first to arrange duplex openings in spaced relation to define a band, the band and sets of openings effectively coacting to not only greatly facilitate the folding of the sections of the hem but accurately determining the lines upon which the folds are to be accomplished, thereby assuring a very neat effect after all folding operations. To accomplish a neat appearance it is absolutely necessary that each foldable portion of the hem be of an equal width throughout and the lower edge of the fold accurately parallel to the upper edge of the fold. It is also important that the folded section be smooth and positively parallel its companion section to facilitate the attachment of the fastener of the garter. Due to the even formation of the folds and the parallel relation of the sections, it will be readily appreciated that the folded hem may be effectively used as a wide band for holding the upper portion of the stocking

in place without the use of a garter, if this is desired in the use of the hosiery.

Of course, it is to be understood that the openings and bands may be constructed in various ways in practice and different shapes of openings may be used than illustrated and therefore I do not desire to be limited in protection in any manner whatsoever except as set forth in the following claims.

10 What I claim is:

1. A stocking provided with a plurality of sets of openings, unequally spaced to define foldable sections in the hem of the stocking progressively increasing in width towards the foot of the stocking whereby the width of the hem may be changed by the folding thereof.

2. A stocking provided with a plurality of sets of openings unequally spaced to define foldable sections in the hem of the stocking progressively increasing in width towards the foot of the stocking whereby the width of the hem may be changed by the folding thereof, each set of openings consisting of several groups of openings encircling the hem of the stocking in close parallel relation to promote a folding tendency in the hem.

In witness whereof I have hereunto set my hand.

30 **JACK KUGELMAN.**
